FLOW CONTROL DEVICE

James H. Childress, Inglewood, Calif., assignor to
 Pan American Petroleum and Transport Company, New York, N. Y., a corporation of Delaware

Application January 28, 1931, Serial No. 511,763

2 Claims. (Cl. 251—61)

This invention pertains to fluid flow controlling or restricting devices and, more particularly, so far as one valuable use is concerned, to flow restricting or control devices for flowing oil wells. 5 Such devices, commonly known as "flow-beans" may be said to partake of some of the characteristics of a valve but unlike most valves, they do not function to stop or shut-off the fluid flow; instead they merely restrict or control the flow of 10 oil and gas and serve to maintain a back pressure or "head" on these fluids on the up-stream side of the device. While the invention will be found useful in other fields than the field of oil production, it finds one of its most important and 15 advantageous uses in the latter field, for which reason it will be illustrated and described in its application thereto.

Many flowing oil wells produce a large quantity of sand with the oil. This sand, because of its 20 abrasive action, quickly scores and cuts away the hardest metal with which it comes in contact. As a consequence it has been found impractical to control or restrict the flow of such wells with ordinary valves so "Christmas trees" and "flow-beans" have come into use as a practical solution 25 for the difficulty. It is common practice to provide the flow-pipe or casing, bringing the oil from the well, with a number of branches, each equipped with shut-off valves (high and low pressure) and 30 a replaceable section or connection carrying a flow-bean. The flow-beans are placed down stream from the shut-off valves and between the valves and a flow-line to a flow station, a settling tank or other place of disposal for the oil and in 35 some instances the branch pipes may all connect with a single flow line to the same place of oil disposal. With an arrangement, such as last mentioned, the valves in one branch will be closed while the valves in another branch are open. 40 When, however, the flow-bean in the operating branch is worn out (ground away by sand flow) that branch is shut down and another branch opened, the first flow-bean being replaced while the second is operating.

45 The cost in labor, effort and time involved in changing the flow from one branch line to another and in replacing the flow-beans, as well as the cost of installation and maintenance of the several branch lines, etc., is a serious matter under 50 ordinary circumstances but becomes increasingly so in connection with those wells which expel, with the oil, very large quantities of sand per unit of time. There are instances of record where it has been necessary to maintain one man constantly at the well head doing nothing but replace

flow-beans as fast as they wore out, the man working continuously, first closing the valves in one branch line and opening the valves in another, then replacing the flow-bean in the first line, then opening the valves in the first branch and closing the valves in the second, then replacing the flow-bean in the second branch, and so on, for indefinite periods of time. Such arrangements and methods are not only costly and difficult but are objectionable for many other reasons; yet to my knowledge, at this writing, no one prior to my invention has devised a satisfactory means or method to replace them.

5 10 One of the primary objects of my invention is to provide an arrangement and a device whereby the flow-beans may be replaced and renewed, cheaply, quickly and with a minimum of labor and whereby, if it should be desired, the ordinary "Christmas tree" or considerable portions thereof may be omitted or rendered unnecessary.

15 20 Many other objects, as well as the advantages, uses and purposes of the invention will be or should become apparent to those skilled in the art, after reading the description and the claims and after viewing the drawings, in which:

25 Fig. 1 is an elevational view, partially in section and somewhat diagrammatic, illustrating one embodiment of the invention and its application to one form of well head equipment.

30 Fig. 2 is an enlarged and elevational view of the form of the invention illustrated in Fig. 1.

35 Fig. 3 is a sectional view of the same taken along the line III—III of Fig. 2, but drawn to a greater scale, and

Fig. 4 is a view taken substantially along the line IV—IV of Fig. 2.

40 45 The well casing 2 is secured and sealed within the earth 3 by concrete grouting 4, which also may be extended over the top of the ground, as shown at 5, to provide a suitable surface and support for structure which may be mounted upon it. Neither the details of this construction nor the arrangement thereof, nor the details of the inner casing 6, the flow tube 7 and the coupling devices 8 and 9, have any special connection with the invention and have been shown and are here described merely for the purpose of providing a setting, the better to depict the embodiment of the invention chosen for exemplification. Indeed these parts and the arrangement as thus far described, together with the drilling-through valve 11 shown in the casing, constitute merely one form of hook-up which may be encountered and for such reason it should be understood that the invention is not limited in any way thereby, but 50 55

is of broad application to hook-ups bearing no resemblance to the present one.

In ordinary practice, a pipe 12 leads into a cross fitting, such as that designated 13, from which branches 14 and 15 lead off through valves 16 and 17 respectively, to the same or different flow lines leading to one or more flow stations from which the oil is led to storage or to some other place of disposal. In some cases pipe 12 10 may be continued on upwardly and connected with another cross fitting, from which branch pipes again lead off after the manner just described. Very often the top opening of the top cross fitting will be closed by what is commonly 15 known as a bull plug, such as that designated 18, to which a pressure gauge 19 may be connected. A rig or arrangement such as that thus far described, is commonly known as a "Christmas tree", the aptness of which expression is at once 20 apparent.

With my invention, it may be unnecessary to have more than one branch pipe or flow line and if the "Christmas tree" is already constructed, I 25 may close off all branch lines but one by the use of bull plugs, as is illustrated at 21, or in any other suitable manner. However, it may be desirable to have no interruption to the flow in which case there may be several flow lines in 30 operation. A short length of pipe or a nipple 22 is connected to the valve 17 and a coupling 23 may connect my invention which, in the form illustrated, is generally designated 24, with the pipe or nipple 22 and into the flow line. If it be 35 desired to prevent even a short interruption to flow during the changing of beans, another of the devices 24 may be connected in the line leading from the valve 16, in which case one will be in operation while the other is being changed or repaired.

The device 24 comprises a heavy steel or other 40 suitable metal body 25, formed in the shape of a cross, as best illustrated in Fig. 3, and bored through along the axis of the arms of the cross to provide bores 26 and 27 at right angles to one 45 another. A riser, boss or flange 28, forming one arm, and a riser, boss, or flange 29, forming an opposite arm, may be suitably threaded, as shown at 30 and 31 respectively, for connection in the flow line, but they may be coupled in the flow 50 line in any other suitable manner. The bore through the riser 28, the flow being from left to right in Fig. 3, preferably converges inwardly toward the bore 27, as indicated at 32, to provide with the rest of the flow passage, etc. a venturi, 55 while the cross bore 27 is counter bored in the risers or flanges 33 and 34, to provide stuffing bosses or packing recesses 35 and 36 respectively.

Within the bore 27, a core or bar, or plunger, 60 as it may be variously termed, and generally designated 37, is tightly but slidably or reciprocably mounted. This plunger, in the present embodiment, is of cylindrical shape but obviously it may be of any shape in cross section satisfactory for the purposes it is to serve although practical difficulties may be encountered in making 65 it of other than cylindrical external contour. Packing 38 is placed within the stuffing bosses and is held in place by glands 39 and 41, which are threadedly engaged within the risers or arms 33 and 34. One end of the plunger is provided 70 with an integral head 42, which is slotted inwardly past the center from one edge, as shown at 43, the slot being under-cut, as shown at 44 and 45, to receive a flanged head 46, rotatably carried by 75 or fixed on a threaded stem 47. At its other end,

the plunger is provided with a collar 48, which may be pinned thereto, as by a pin 49, the collar acting to limit movement of the plunger in one direction and the head 42 acting to limit its movement in the opposite direction.

The plunger is transversely bored along parallel axes to provide passages 51 and 52, each of which is adapted to be axially aligned with the axis of the bore 26. Each of the passages 51 and 52 is provided with a circumferentially extending shoulder 53 against which one side of a flow-bean or choke disc 54, 54', respectively, rests and is removably positioned, the choke discs being held in place by removable locking rings 55, threadedly engaged with threads formed in the passages 51 and 52. Each choke disc has a central orifice 56 through which the oil flows from the well to the flow station and the passages 51 and 52 are spaced apart a distance greater than the axial distance between the axis of the bore 26 and 20 the outer ends of the glands 39 and 41, assuming that the outer ends of the glands 39 and 41 are at the same distance from the axis of the bore 26. This spacing of the choke discs of flow-beans must be such that each becomes accessible from the 25 outside as the plunger is reciprocated between its extreme limits of movement. It may be desirable to have the flow from right to left, viewing Fig. 3, to relieve the stress which may otherwise be placed on the threads of the rings 55 and 30 to throw the pressure load directly upon the shoulders 53, but this matter may be left to those skilled in the art.

The stem 47 passes through an aperture 57 formed in a yoke, the arms 58 and 59 of which 35 may straddle and be secured to the body portion 25 as by stud-bolts 61. Mounted upon the top of this yoke is a second yoke 62 with a central aperture within which an internally threaded bushing 63 is secured, for threaded engagement 40 with the threads of the stem 47, while a hand wheel 64 is secured to the upper end of the stem and rotates therewith. It will be observed that as the hand wheel is rotated in the direction of the arrow "R", the threads on the stem 47, being right hand threads, the plunger 37 will be drawn or raised up to interpose the choke disc or flow-bean 54' in the flow line and the flow-bean 54 will be moved to an accessible place outside of the boss or riser 33, as illustrated in Fig. 3, for 45 removal and replacement, whereas, if the plunger is at its uppermost limit, rotation of the hand wheel 64 in the direction of arrow "L" lowers the plunger interposing the flow-bean 54 in the flow line and projecting the flow-bean 54' beyond 50 the limits of the boss or riser 34, so that it may be removed and replaced. When two of the devices 24 are used and a change of beans is 55 desirable or necessary, the one not operating will be set in operation before or simultaneously with the shutting down of the other so that there may be no interruption to the well flow but, of course, other methods of operation may be used.

Inasmuch as the construction in the illustrated embodiment is such that the stem rotates as it 60 rises, some means must be provided to prevent rotation of the plunger 37, which in the present form is cylindrical, because rotation of the plunger would displace the flow-beans out of alignment with the bore or passage 26. To this end a 65 fork shaped guide member 65 is suitably secured to the top of the head 42 of the plunger with its arms embracing the arm 59 of the lower yoke. As the plunger reciprocates, the arms of the member 65 bear against the sides of the arm 59 70 75

and prevent the plunger from working out of alignment. Resort may be had to other arrangements to prevent rotation of the plunger. The plunger and the bore may be made other than circular in transverse cross section or, if it be desired to maintain the hand wheel 64 at one level at all times, the hand wheel may be threadedly engaged with the stem for rotation with respect thereto and provided with a suitable thrust collar for engagement with upper and lower thrust bearing surfaces secured to or forming part of the yoke 62. In this latter case the stem will not rotate and may be non-rotatably secured to the plunger 37, but will have a longitudinal key-way 15 formed along substantially its entire length for engagement with a key which may be secured to the walls defining the aperture 57 or in a lower portion of the yoke 62, below the thrust bearings therein to prevent rotation of the stem. Other 20 arrangements to the same end will be apparent to those skilled in the art.

The advantages of my invention should be apparent. It is a comparatively simple operation when one flow-bean has become worn through the cutting action of sand to remove and replace the bean while the first is being used. The choke or bean changes can be effected against the pressure and the flow without loss of oil, the changes can be effected very rapidly in a simple and economical operation in the form illustrated, the choke disc is the only part of the assembly which is subject to wear and can be made and replaced very cheaply, and the device effects considerable savings in material and parts, actually permitting, if desired, the elimination of numerous parts heretofore used in "Christmas tree" design. If it be desired to replace any choke with chokes having larger orifices, this may be done; and, if it be found expedient to provide more than two choke passages through the plunger 37, this also may be done without difficulty.

While I have illustrated and described a preferred form of the invention, it will be appreciated that the invention may assume many other forms and that the form illustrated may be considerably modified in various respects. Consequently, I do not desire to be limited except by the spirit of the invention and the scope of the appended claims.

I claim:

1. A flow controlling device comprising a body member having a fluid passageway therethrough, a movable plunger intersecting said passageway between its ends, said plunger having two adjacently spaced openings therethrough adapted to register with said fluid passageway and to establish communication between the ends thereof upon predetermined movement of said plunger, the spacing between the two openings being sufficient to close communication between the ends of said fluid passageway and to permit the adjacent opening to extend to the exterior of the body member when the other opening has registered with the fluid passageway, an orifice-containing member removably secured in each of said openings, a yoke attached to the body member, a threaded stem operatively engaging said yoke for operating the plunger, a means attached to one end of the plunger and coacting with the yoke for preventing rotation of the plunger as it moves into an operative position, and a removable means on the other end of the plunger for limiting the movement of said plunger. 15

2. A flow controlling device comprising a body member having a fluid passageway therethrough, a movable plunger intersecting said passageway between its ends, said plunger having two adjacently spaced openings therethrough adapted to register with said fluid passageway and to establish communication between the ends thereof upon predetermined movement of said plunger, the spacing between the two openings being sufficient to close communication between the ends of said fluid passageway and to permit the adjacent opening to extend to the exterior of the body member when the other opening has registered with the fluid passageway, an orifice-containing member removably secured in each of said openings, a yoke attached to the body member, a means operatively engaging said yoke for operating the plunger, a means attached to one end of the plunger for preventing rotation of the plunger as it moves into an operative position, and a means on the other end of the plunger for limiting the movement of said plunger. 25 30 35 40 45

JAMES H. CHILDRESS.
